UNITED STATES PATENT OFFICE.

OSCAR GUTHERZ, LIMOGES, FRANCE.

DESIGN FOR A TOP OF A CUSPIDOR.

SPECIFICATION forming part of Design No. 13,516, dated January 9, 1883.

Application filed November 16, 1882. Term of patent 7 years.

To all whom it may concern:

Be it known that I, OSCAR GUTHERZ, of Limoges, France, have invented a new and Improved Design for the Tops of Cuspidors, of which the following is a full, clear, and exact description.

Reference is to be had to the accompanying drawings, forming part of this specification, in which similar letters of reference indicate corresponding parts in both the figures.

Figure 1 is a plan view of my newly-designed cupidor-top, and Fig. 2 is a sectional side elevation of the same.

The leading feature of my design is the square flaring shape of the top, made with truncated corners, as will be hereinafter fully described.

A is the top or flange of the cupidor, which is made square and with truncated corners B

in its general contour. The truncated corners 20 can be made with a flat or a slightly-convexed upper surface, as may be desired. The top A is made flaring and the inclination may be varied without departing from my design.

In the illustration given the top A B is shown 25 as being smaller than the body C; but this is not essential, as the said top and body may have any desired relative size.

I claim—

The design for a cupidor-top herein shown 30 and described, the same consisting of the flaring square top having truncated corners, as set forth.

OSCAR GUTHERZ.
